UNITED STATES PATENT OFFICE.

ALFRED GEORGE RIESKE, OF BUFFALO, NEW YORK.

DEVICE FOR PLUCKING FOWLS.

1,323,492.

Specification of Letters Patent.

Patented Dec. 2, 1919.

Application filed December 21, 1918. Serial No. 267,807.

To all whom it may concern:

Be it known that I, ALFRED GEORGE RIESKE, of the city of Buffalo, in the State of New York, United States of America, 5 have invented certain new and useful Improvements in Devices for Plucking Fowls, of which the following is a specification.

This invention relates to devices for plucking fowl comprising devices for pulling or loosening the feathers and pneumatic means for carrying away the loosened feathers. In such devices the provision of means for pulling or loosening the pin feathers is the most difficult problem to be 10 solved, and the present application relates to means for extracting the pin feathers which will be both effective and durable.

The invention is illustrated in the accompanying drawings in which—

20 Figure 1 is a face view of the under side of the suction head of a fowl plucking device constructed in accordance with my invention;

Fig. 2 an end elevation of the same with 25 the end cap removed;

Fig. 3 a cross section showing the plucking parts in their initial position;

Fig. 4 a similar view showing the parts in 30 the position they assume with a feather partly pulled;

Fig. 5 a similar view showing the gripping member about to disengage from the plucker blade;

Fig. 6 a perspective detail of the gripping 35 device;

Fig. 7 a perspective detail of the plucker bar; and

Fig. 8 an end view of the casing with the outer end removed.

40 In the drawings like numerals of reference indicate corresponding parts in the different figures.

1 is a hollow suction head provided at its under side with a suction opening or slot 45 2. 3 is a connection formed on the suction head whereby the suction head may be connected with a suitable suction hose. Across the suction opening is secured a comb 4, which is preferably formed as a grating, the 50 teeth of the comb being connected at their points as well as at their bases and the head between the teeth sharpened to a knife edge.

On the suction head and within the same 55 is mounted a plucker blade 5. This blade is so mounted as to be reciprocable to and from a position with its forward edge in an

initial feather gripping position, which will usually be along a line substantially coincident with the bases of the teeth of the comb 4. Preferably this plucker blade is 60 arranged to reciprocate on an arc of a circle concentric with the interior wall of the suction head, which is cylindrical.

In the drawings the suction blade is shown as connected to arms 6, to which are 65 connected trunnions 7 journaled concentrically in the ends of the suction head. The outer end 8 of the suction head is preferably made removable for convenience in assembling the device. The plucker blade is provided with means for imparting to it the 70 reciprocating movement hereinbefore referred to. Movement to the initial feather gripping position is preferably effected by means of a coil spring 9, which is located in an annular slot formed in the end 8. One end of this coil spring engages a pin 10 formed on or secured to the outer arm 6 and extending through an arc shaped slot 11 formed in the end 8. The forward end of 75 the slot limits the forward movement of the plucker blade. The other end of the coil spring engages an abutment 12, which abutment is preferably movable in the groove in the end 8 and may be secured in position by 80 means of a screw 13 engageable with any one of two or more holes formed in the end. By adjusting the position of the abutment 12, the tension of the coil spring 9 may be 85 regulated as desired.

To move the plucker blade back from the initial feather gripping position, I employ a movable device which serves also as a gripping device to grip the pin feathers against the forward edge of the plucker blade. In 90 the preferred arrangement, one or more grippers 14 are provided so carried and moved as to engage with and press back the plucker blade, afterward passing by and releasing the plucker blade to allow the latter 100 to return to its initial position under the action of the coil spring 9. The preferred arrangement is to mount one or more grippers on a frame 15 journaled in the ends of the suction head. One journal 16 extends 105 from a bearing in the head and serves for the connection of a flexible shaft or other means of imparting a rotary motion thereto.

While the forward edge of the plucker blade and the engaging faces of the grippers may be given many different forms which would answer the purpose of my in-

vention, I prefer to bevel the forward edge 17 of the plucker blade inwardly and rearwardly and also to give it a slightly concave form. The forward edge of each gripper is also preferably convexed and the journals of the frame 15 so located that the point of closest contact between a gripper and the plucker bar as the gripper bar is pushed back takes place a little back of the 10 extreme edge of the plucker blade and therefore midway between the extreme end of a pin feather and the skin of the bird from which it is being extracted. This arrangement is adopted on account of the tapering 15 shape of the pin feather, which necessitates its being gripped at a point where its diameter is substantially the mean between the two extremes. While the gripper may be a fixture on the frame 15, good results 20 may be obtained by forming the grippers of rollers journaled on the frame 15. In Fig. 4, one gripper is shown as a fixed bar and the other as a roller. It will be noted that the grippers are separated by a space 25 so that when the parts are in the position shown in Figs. 4 and 5, a direct passageway through the head is formed from the comb so that efficient suction of air is obtained to carry off the pulled and loosened 30 feathers. To insure a constant flow a second opening 18 may be provided in the suction head back of the plucker blade.

The device is used as follows. The operator holds the bird to be plucked of pin 35 feathers with one hand and pushes the suction head over the bird's skin with the other hand, the comb 4 being maintained substantially parallel to the direction in which the feathers lie. The device is pushed, so 40 to speak, against the grain so that the projecting ends of the pin feathers are lifted by the forward beveled edge of the plucking blade to a position to be gripped against the blade by one of the grippers. Thereafter 45 the gripper as it moves securely holds the feathers against the blade and at the same time moves the latter to pull the feathers, which are then, when released by the gripper, quickly sucked away by the air current maintained through the suction 50 head.

What I claim as my invention is:—

1. In fowl plucking apparatus, a suction head having a suction slot formed therein and provided with a reciprocating plucker blade movable to and from an initial feather gripping position in said slot; and a co-operating gripper movable to co-act with the plucker blade and maintain engagement therewith during the pulling movement thereof.

2. In fowl plucking apparatus, a suction head having a suction slot formed therein and provided with a reciprocating plucker 65 blade movable in a direction from front to

back of the slot to and from an initial feather gripping position in said slot; and a co-operating gripper movable to co-act with the plucker blade and maintain engagement therewith during the pulling 70 movement thereof.

3. In fowl plucking apparatus, a suction head having a suction slot formed therein and provided with a reciprocating plucker blade movable to and from an initial 75 feather gripping position in said slot; a co-operating gripper movable to co-act with the plucker blade and to impart the pulling movement thereto by its direct engagement therewith; and spring means 80 tending to return the plucker blade to its initial position.

4. In fowl plucking apparatus, a suction head having a suction slot formed therein and provided with a reciprocating plucker 85 blade movable to and from an initial feather gripping position in said slot; a co-operating gripper rotatably mounted to co-act with the plucker blade to impart the pulling movement thereto by its direct engagement 90 therewith and thereafter to pass by and release the plucker blade; and spring means tending to return the plucker blade to its initial position.

5. In fowl plucking apparatus, a suction 95 head having a suction slot formed therein and provided with a reciprocating plucker blade movable to and from an initial feather gripping position in said slot; a plurality of co-operating grippers rotatably 100 mounted on a common axis each adapted to co-act with the plucker blade to impart the pulling movement thereto and thereafter to pass by and release the plucker blade; and spring means tending to return the plucker 105 blade to its initial position.

6. In fowl plucking apparatus, a suction head having a suction slot formed therein and provided with a reciprocating plucker blade movable to and from an initial 110 feather gripping position in said slot, said blade having its forward edge beveled inwardly and rearwardly; a co-operating gripper rotatably mounted to co-act with the plucker blade to impart the 115 pulling movement thereto by its direct engagement therewith and thereafter to pass by and release the plucker blade; and spring means tending to return the plucker blade to its initial position.

7. In fowl plucking apparatus, a suction head having a suction slot formed therein and provided with a reciprocating plucker blade movable to and from an initial feather gripping position in said slot; a co-operating 125 gripper roller; a rotatable frame on which said roller is eccentrically journaled so that by the rotation of the frame it may be moved to co-act with the plucker blade to impart the pulling movement thereto and 130

thereafter to pass by and release the plucker blade; and spring means tending to return the plucker blade to its initial position.

8. In fowl plucking apparatus, a suction head having a suction slot formed therein and provided with a reciprocating plucker blade movable to and from an initial feather gripping position in said slot; a coöperating gripper movable to co-act with the plucker 10 blade and maintain engagement therewith during the pulling movement thereof; and a comb located over and covering said opening with the bases of its teeth substantially in alinement with the forward edge of the 15 plucker blade when the latter is in its initial position.

9. In fowl plucking apparatus, a suction head having a suction slot formed therein and provided with a reciprocating plucker 20 blade movable in a direction from front to back of the slot to and from an initial feather gripping position in said slot; a coöperating gripper movable to co-act with the plucked blade and maintain engagement 25 therewith during the pulling movement thereof; and a comb located over said opening with the bases of its teeth substantially in alinement with the forward edge of the 30 plucker blade when the latter is in its initial position.

10. In fowl plucking apparatus, a suction head having a suction slot formed therein and provided with a reciprocating plucker blade movable to and from an initial feather 35 gripping position in said slot; a coöperating gripper movable to co-act with the plucker blade and to impart the pulling movement thereto by its direct engagement therewith; spring means tending to return the plucker 40 blade to its initial position; and a comb located over said opening with the bases of its teeth substantially in alinement with the forward edge of the plucker blade when the latter is in its initial position.

45 11. In fowl plucking apparatus, a suction head having a suction slot formed therein and provided with a reciprocating plucker blade movable to and from an initial feather gripping position in said slot; a coöperating 50 gripper rotatably mounted to co-act with the plucker blade to impart the pulling movement thereto by its direct engagement therewith and thereafter to pass by and release the plucker blade; and spring means tending to return the plucker blade to its 55 initial position; and a comb located over said opening with the bases of its teeth substantially in alinement with the forward edge of the plucker blade when the latter is in its initial position.

60 12. In fowl plucking apparatus, a suction head having a suction slot formed therein and provided with a reciprocating plucker blade movable to and from an initial feather

gripping position in said slot; a plurality 65 of coöperating grippers rotatably mounted on a common axis each adapted to co-act with the plucker blade to impart the pulling movement thereto and thereafter to pass by and release the plucker blade; spring means 70 tending to return the plucker blade to its initial position; and a comb located over said opening with the bases of its teeth substantially in alinement with the forward edge of the plucker blade when the latter is 75 in its initial position.

13. In fowl plucking apparatus, a suction head having a suction slot formed therein and provided with a reciprocating plucker blade movable to and from an initial feather 80 gripping position in said slot, said blade having its forward edge beveled inwardly and rearwardly; a coöperating gripper rotatably mounted to co-act with the plucker blade to impart the pulling movement there- 85 to and thereafter to pass by and release the plucker blade; spring means tending to re- turn the plucker blade to its initial position; and a comb located over said opening with the bases of its teeth substantially in 90 alinement with the forward edge of the plucker blade when the latter is in its initial position.

14. In fowl plucking apparatus, a suction head having a suction slot formed therein 95 and provided with a reciprocating plucker blade movable to and from an initial feather gripping position in said slot; a coöperating gripper roller; a rotatable frame on which said roller is eccentrically journaled so that 100 by the rotation of the frame it may be moved to co-act with the plucker blade to impart the pulling movement thereto and thereafter to pass by and release the plucker blade; spring means tending to return the 105 plucker blade to its initial position; and a comb located over said opening with the bases of its teeth substantially in alinement with the forward edge of the plucker blade when the latter is in its initial position. 110

15. In fowl plucking apparatus, a suction head having a suction slot formed therein and provided with a reciprocating plucker blade movable to and from an initial feather gripping position in said slot; a plurality 115 of coöperating grippers rotatably mounted on a common axis with a clear space be- between them for the passage of air and each adapted to co-act with the plucker blade to impart the pulling movement thereto and 120 thereafter to pass by and release the plucker blade; and spring means tending to return the plucker blade to its initial position.

16. In fowl plucking apparatus, a suction head having a suction slot formed therein 125 and provided with a reciprocating plucker blade movable to and from an initial feather gripping position in said slot; a coöperating

gripper movable to co-act with the plucker blade and maintain engagement therewith during the pulling movement thereof; and a comb located over said opening with the bases of its teeth substantially in alinement with the forward edge of the plucker blade

when the latter is in its initial position, the head of the comb between the teeth being sharpened to a knife edge.

Signed at Buffalo, Erie county, N. Y. this 10
nineteenth day of December 1918.

ALFRED GEORGE RIESKE.
